UNITED STATES PATENT OFFICE.

WILLIAM C. LOCKWOOD, OF CHICAGO, ILLINOIS, ASSIGNOR TO LOCKWOOD
TELEPHONE COMPANY, OF SAME PLACE.

TELEPHONE.

SPECIFICATION forming part of Letters Patent No. 233,360, dated October 19, 1880.

Application filed January 27, 1880.

To all whom it may concern:

Be it known that I, WILLIAM C. LOCKWOOD, of Chicago, Illinois, have invented a new and useful Improvement in Telephones, of which 5 the following is a specification.

The invention consists in a magnet made adjustable in two paper chambers toward and from the diaphragm, a combination diaphragm, and a soft-metal mouth-piece, and also the 10 means shown for intensifying the power of the magnet, all of which is hereinafter more particularly described and shown, reference being made to the accompanying drawings, in which—

15 Figure 1 is a perspective, showing the top and front of the box and magnet-chambers in which the parts are arranged. Fig. 2 is a rear view of the same, a part of the outer box being removed. Fig. 3 is a longitudinal horizontal section on the line x x , Fig. 2, and Fig. 20 4 is a longitudinal vertical section on the line x x , Fig. 3.

Like letters of reference indicate like parts in the several figures of the drawings.

25 A is the outer box, which may be made of wood most conveniently. A' is a cylindrical chamber, made of paper, and having attached at the front end the smaller cylindrical chamber A², extending beyond the box A.

30 E is a straight magnet, which passes through the chambers A' A², and is provided with electric wire coils or spools E' E², of the usual construction, and rubber spring F, rubber packing F', and a screw-thread with the nut G at 35 the rear end. By means of the screw and nut and the rubber spring the magnet may be adjusted toward or from the diaphragm.

B is the mouth-piece, made of soft metal—that is, cast or malleable iron not hardened in 40 any way, that being the best metal for containing or affecting magnetism. The object and effect of such mouth-piece arranged outside of a telephone-diaphragm is to extend or increase the magnetic attraction or influence 45 outside of the diaphragm, and thereby affect the action of the magnet upon the diaphragm in an increased degree, making the diaphragm more sensitive to the sound of the voice, and so giving a louder and firmer tone to the instrument. I have ascertained by experiment 50

that such metal mouth-piece so placed produces the result stated.

The diaphragm is formed of a silver plate, C, having a circular opening in the center, and a mica plate, D, located just behind the plate 55 C. Between the plates C and D and the plate C and soft-metal mouth-piece B are placed rubber or insulating rings C', to prevent the contact of said plates with each other and with the mouth-piece.

A³ A⁴ are cylindrical chambers, made of paper, and located just outside and on opposite sides of the chamber A' and partially within the box A. These chambers A³ A⁴ contain 60 wire coils or spools E³ E⁴, and the space between the spools and circular walls of these chambers is filled with mixed ground emery and magnetized iron filings.

H H' H² H³ are the wires running from the spools E' E² E³ E⁴, of which H H' connect the 70 spool E' to the rear of the chamber A' by means of screw-pegs h h', (see Fig. 2,) one of these two wires being extended from its peg to the ground and the other being connected to the transmitting-line, and H² H³ are extended out 75 from the spools E³ E⁴ and connected with a battery of the usual construction. (Not shown.)

By means of the spools and their connections the power of the magnet is increased at least fourfold, and the paper chambers in which 80 the magnet is inclosed are highly sonorous.

The diaphragm formed of the silver plate, with its opening and the mica plate arranged as shown, is exceedingly sensitive to vibrations or air-waves, and the magnet is made adjustable backward or forward to the diaphragm, for the purpose of adapting the instrument to the various changes of atmosphere and circumstances to which its use at different times and in different localities may subject it, and the 85 whole arrangement of the parts is intended to secure the best results.

Having thus described my invention, what I claim, and desire to secure by Letters Patent, is—

1. The magnet E, passing through paper chambers A' A², and made adjustable in the direction of its length by means of the rubber spring F and thumb-screw G, substantially as and for the purpose specified.

2. In a telephone, the diaphragm composed of the open silver plate C and mica plate D, insulated by ring C', substantially as and for the purpose specified.
- 5 3. In combination with the diaphragm of a telephone, the soft-metal mouth-piece B, insulated from the diaphragm by a ring, C', substantially as and for the purpose specified.
4. In a telephone, the combination of a magnet, E, with coils E' E² E³ E⁴, connected and inclosed in paper chambers, substantially as and for the purpose specified.

WILLIAM C. LOCKWOOD.
